UNITED STATES PATENT OFFICE.

EDWIN BALL STIMPSON, OF BROOKLYN, NEW YORK.

CARTRIDGE-BELT.

1,288,262.

Specification of Letters Patent. Patented Dec. 17, 1918.

Application filed May 14, 1918. Serial No. 234,542.

To all whom it may concern:

Be it known that I, EDWIN BALL STIMPSON, a citizen of the United States, residing at Brooklyn, county of Kings, and State 5 of New York, have invented certain new and useful Improvements in Cartridge-Belts, of which the following is a specification.

My invention relates to cartridge feeding belts of the type used in rapid fire machine 10 guns, and has for its object to provide an improved belt formed of unsubstantial sheet material having reinforcing tensile members embedded therein.

In an application for patent, Ser. No. 15 233,553, filed by me on May 9, 1918, a cartridge belt of this general type was shown and described which consisted of two strips of light and unsubstantial sheet material, such as paper, reinforced along the center 20 and at either edge with a cord or thread designed to increase the tensile strength of the belt as a whole. The two strips making up the belt were preferably attached to each other by stitching together spaced portions 25 of the threaded portions at suitable intervals to form cartridge holding loops. This form of cartridge belt is highly satisfactory and serviceable, but as I have continued my experiments, I have developed another arrangement of the reinforcing threads and 30 so utilized the new arrangement that an improved manner for forming the cartridge holding loops has resulted, and consequently a generally improved form of belt of this 35 general nature has been obtained.

The principal feature of the invention resides in the formation of a belt by means of two superposed strips of material such as paper, each strip having a plurality of reinforcing cords spaced apart and embedded therein along each lateral edge thereof, together with means for attaching the strips to each other at points between the adjacent reinforcing cords, to form suitable cartridge 45 holding loops.

Other features of the invention will be hereinafter described.

In the drawings,

Figure 1 is a view of a section of cartridge 50 belt embodying a preferred form of the invention and showing a number of cartridges in place therein.

Fig. 2 is a view similar to Fig. 1 and showing a modified form of means for attaching the belt strips together.

Fig. 3 is a view of a section of belt show-

ing the use of metallic clips for clamping the strips together to form the belt.

Fig. 4 is a view showing the use of an ordinary form of staple with which the 60 strips are attached together.

Fig. 5 is an enlarged sectional view showing the folded paper strips used to make up the belt.

The cartridge feeding belt shown in the 65 drawing comprises the strips 1 and 2 formed of double strips of material such as paper or the like, having two sets of reinforcing cords 3 and 4 embedded therein in two 70 slightly spaced apart positions along each lateral margin of the strips. The reinforcing cords 3 and 4 are preferably of such a nature as to offer a very substantial resistance to breaking, so that they add in an important degree to the tensile strength of 75 the belt as a whole.

The belt-forming strips are preferably attached to each other at suitably separated points to form cartridge holding loops by means of metallic fastening members taking 80 various forms. I have found eyelets 5, such as are shown in Fig. 1, to be well suited to the purpose in view, and by placing them in oppositely disposed positions between the parallel reinforcing cords 3 and 4, near each 85 lateral edge, any tendency that the material might otherwise have to tear as it is bent over the edge of the eyelet is eliminated, since the tension on the strip or web is taken up by the reinforcing cords. This makes 90 a very effective construction and the eyelets can be rapidly fastened in place in making up the belts. It will be seen that the eyelet members 5 are wider near one margin of the belt than the other so as to form holding 95 loops of different size to fit the correspondingly different diameters 6 and 7 of the cartridges.

It will be seen that by placing the reinforcing cords in groups, and preferably in 100 pairs, and making use of fastening members that exert their clamping effect on substantially the entire width of the material between the cords in each pair, the cords are held in immovable relation with respect to 105 each other and one cord cannot be pulled to a more advanced point than another. This has a very important result in that any tendency which the belt may otherwise have had to yield in such a way as to allow one edge to be pulled to a position in advance 110 of the other and thus destroy the precise

right angled position of the cartridge to the longitudinal axis of the belt, is effectually eliminated.

While eyelet fastening means applied in the manner indicated in Fig. 1 are the preferred form of construction, it is possible to utilize other ways of attaching the strips together and secure the advantages to be had by grouping a plurality of cords along each margin of the belt strips. In Fig. 2 of the drawing I have shown the use of eyelet members 5 placed in such position with relation to the reinforcing cords that the flanges of the eyelets overlap the cords on either side and thus provide a very secure and effective construction.

Still another form of fastening means that is well adapted to the purpose is shown in Fig. 3 of the drawing in the form of clip members 8 which are bent into place from opposite edges of the strips and are sufficiently long to extend across both adjacent threads in the manner indicated. In Fig. 4 of the drawing the use of staples 9 is shown and it will be seen that in each form of the invention ordinary and well known forms of metallic paper fastening devices are made use of to attach the belt strips together to provide a belt structure sufficiently well reinforced by the reinforcing cords to withstand any strain to which it is likely to be subjected; to rigidly hold the cartridges in the proper position for feeding; and, at the same time, provide a construction that is much lighter, takes up less space, and is a great deal less expensive than cartridge belt constructions now known and used.

Having thus described my invention, what I claim and desire to secure by Letters Patent of the United States is:

1. A cartridge belt comprising: two strips of paper having a plurality of reinforcing tensile members attached thereto at each lateral edge, and means for attaching the strips together at separated points along the reinforced portions to thereby form cartridge holding loops.

2. A cartridge belt comprising: two strips of paper having a plurality of spaced apart reinforcing cords embedded therein along each lateral edge, and means for attaching the strips together at separated points in the spaces between the reinforcing cords to thereby form cartridge holding loops.

3. A cartridge belt comprising: two strips

of paper having a plurality of spaced apart reinforcing cords embedded therein along each lateral edge, and means for attaching the strips together at oppositely disposed separated points along the reinforcing cords to thereby form cartridge holding loops.

4. A cartridge belt comprising: two strips of paper having a pair of spaced apart reinforcing cords embedded therein along each lateral edge, and means for attaching the strips together at separated points to form cartridge holding loops, said attaching means being arranged to clamp together oppositely disposed portions in each pair of cords and the intermediate web sections.

5. A cartridge belt comprising: two strips of paper having a pair of spaced apart reinforcing cords embedded therein along each lateral edge, and integral fastening members arranged to attach the strips together at separated points along the reinforced portions formed by each pair of cords.

6. A cartridge belt comprising: two strips of paper having a pair of spaced apart reinforcing cords embedded therein along each lateral edge, and metallic fastening members arranged to fasten the strips together at separated points along the reinforced portions formed by each pair of cords.

7. A cartridge belt comprising: two strips of paper having a pair of spaced apart reinforcing cords embedded therein along each lateral edge, and eyelet members arranged to fasten the strips together at separated points along the reinforced portions formed by the reinforcing cords.

8. A cartridge belt comprising: two strips of paper having a pair of spaced apart reinforcing cords embedded therein along each lateral edge, and eyelet members arranged to fasten the strips together at separated points along the spaces between the spaced apart cords to thereby form cartridge holding loops.

9. A cartridge belt comprising: two strips of paper having a pair of spaced apart reinforcing cords embedded therein along each lateral edge, and eyelet members inserted in the spaces between the spaced apart cords and having the flanges thereof arranged in overlapping relation to the adjoining cords.

Signed at Brooklyn, in the county of Kings, and State of New York, this 9th day of May, 1918.

EDWIN BALL STIMPSON.
